The ornamental design for a prize wheel, as shown and described.

DESCRIPTION

FIG. 1 is a front, top perspective view of a prize wheel showing my new design;

FIG. 2 is a rear, top perspective view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a top plan view thereof.

The bottom view is omitted as it is not visible during normal use and forms no part of the claimed design.
